UNITED STATES PATENT OFFICE.

JOHN J. COOK, OF CHICAGO, ILLINOIS.

LAMP-CORD CONNECTER.

Application filed July 2, 1923. Serial No. 649,129.

To all whom it may concern:

Be it known that I, JOHN J. COOK, a citizen of the United States, and a resident of Chicago, in the county of Cook and State 5 of Illinois, have invented a new and useful Improvement in Lamp-Cord Connecters, of which the following is a full, clear, and exact description.

My invention relates to improvement in 10 lamp cord connecters and particularly that type of connector employed to secure the pull chain of the electric lamp socket to an ornamental cord, as in the case of stand lamps, and it consists in the combinations, 15 constructions, and arrangements herein described and claimed.

An object of my invention is to provide a 20 connector of the character described that is pleasing in appearance and which covers the union between the electric lamp socket chain and the pull cord completely.

A further object of my invention is to provide a device of the character described which may be quickly and easily applied 25 without the use of special tools, and which may be used indefinitely without appreciable wear.

A further object of my invention is to provide a device of the character described 30 which is simple in construction, compact in form, and thoroughly practical commercially.

Other objects and advantages will appear in the following specification, and the novel 35 features of the invention will be particularly pointed out in the appended claim.

My invention is illustrated in the accompanying drawings, forming part of this application, in which—

40 Figure 1 is a side elevation of an embodiment of my invention,

Figure 2 is an enlarged sectional view of the mechanism illustrated in Figure 1,

Figure 3 is a fragmentary view of a portion 45 of the ornamental lamp cord, and

Figure 4 is an enlarged side elevation of a modified form of my invention.

In carrying out my invention, I make use 50 of an electric light socket having a switch for operating the socket and a pull chain 1 for operating the switch mechanism. This structure is common in the art and well known throughout this country and foreign lands where electric light is made use of.

55 In most cases the pull chain 1 consists of a plurality of metal balls fixed one to an-

other by slender links 3 (see Figure 2). The ordinary practice is to place an enlarged ball at the lower extremity of this pull chain by means of which the chain may be manually grasped and pulled to operate the switch mechanism.

This structure, however, is not particularly ornamental and in carrying out the artistic designs of our more carefully constructed lamps and particularly stand lamps, silk cords having ornamental tassels or the like thereon are fixed in some manner to the chain 1 so that the ornamental cord alone is seen below the shade of the lamp. This 70 is done by cutting the chain 1 off relatively close to the lamp socket and using some securing means.

Heretofore this securing means was one of unsightly construction or construction 75 which calls for particular skill in applying the connector and not one which might be easily applied by anyone wishing to change the ornamental cords and wishing to remove them for cleaning and the like.

80 My improved connector consists solely in a conical sleeve 4 having its smaller end drawn inwardly, as shown at 5, to a diameter slightly larger than the diameter of the balls 2 of the chain 1, there being just 85 enough clearance to permit the balls to pass therethrough.

This conical sleeve 4 tapers gracefully from a diameter at its upper end substantially the same as the diameter of the balls 90 2 to a diameter at its lower end which is in keeping with the thickness or width of the ornamental cord which is to be fastened to the chain thereby.

I have shown these chains in Figure 1 and 95 in the present case the cord 5_a is provided with a loop 6 at its upper end and a tassel 7 at its lower end. This is only one of the many types of cords which may be employed.

100 In fixing the cord 5_a to the chain 1, I open the loop 6, as shown in Figure 3, and pierce the cord to form an opening 8 by means of which one or two of the balls 2 may be projected therethrough. If the cord 105 5_a is constructed of smaller cords twisted about one another, it is merely necessary to separate these cords from the remainder to form the opening 8.

110 The loop 6 is then reestablished and the tubular sleeve 4 is permitted to drop down from the upper end of the chain 1, where-

upon it is manually passed into close engagement with the upper end of the loop 6 of the cord 5_a. It is then in the position shown in Figure 2. The cord 5_a at this time is securely fixed against dislodgment from the chain 1, due to the fact that it may not move laterally adjacent the upper end of the loop and therefore move out of engagement with the balls 2 of the chain.

10 This is because the tapering inner walls of the conical sleeve 4 virtually jam the cord into the spaces between the balls 2 to prevent movement of the cord.

In Figure 4 I have shown a modified form 15 of my invention which is merely another method of securing the cord 5_a to the chain prior to the application of the conical sleeve 4. In Figure 4 I have shown a twisted ornamental cord 5_a and it is not provided 20 with a loop at its upper end. When this form of the cord is employed, it is merely necessary to tie a knot 9 at its upper end and to manually twist the adjacent portions of the twisted smaller cord about the balls 2.

25 The tubular sleeve 4 is then lowered upon that portion of the cord engaging the balls 2 and the cord is held securely against movement relative to the chain.

One of the outstanding advantages of my 30 improved lamp cord connector is that because of the fact that the tubular members

taper, ornamental cords of various diameters may be employed and secured by means of my connector without making it necessary to have a connector of a particular size for a particular size cord, which provision is found necessary in certain of the ordinary types of connecting means known at the present time. If the ornamental cord is a relatively small cord, the cord will be 40 jammed against the inner walls of the connector adjacent its upper end, while if the cord is a relatively heavy cord, it will be pressed into contact with the inner walls of the connector adjacent the lower end. This 45 self-adjusting feature which permits the use of cords of various sizes without change in the size of the connector, I deem to be of utmost importance and the essence of my invention.

I claim:

A lamp cord connector of the character described comprising a tubular sleeve tapering at its lower end and having an inside diameter at its narrow end sufficiently large 55 to permit the passage of an ordinary electric light socket pull chain therethrough, and having an inside diameter at its larger end sufficiently large to permit the introduction of an ornamental lamp cord therethrough.

JOHN J. COOK.
